HOLDING MEANS FOR SHEET MATERIAL
Frank A. Hutter, 6615 Franklin Ave., Hollywood 28,
Calif., and Edward J. Malek, 2833½ Huron St., Los
Angeles, Calif., assignors of one-third to Charles G.
Hutter, Beverly Hills, Calif.

Filed July 11, 1963, Ser. No. 294,346
12 Claims. (Cl. 211—45)

This invention relates to a holder means for pliant, flexible sheet or fabric material and more particularly to a means which readily receives and grips such sheet-like material, such as a towel, and which also quickly and simply releases the towel when the towel is pulled in a certain manner.

Prior proposed holder devices have utilized opposed internal surfaces on a pair of spaced members and a loose ball which served as a movable locking element for engagement with a portion of a towel or fabric received between the ball and one or both of the surfaces. Such prior devices operated in a generally satisfactory manner but included several disadvantages or limitations including difficult release of the towel, special care was required for insertion of the towel into the device, and pulling or tugging the towel from a sidewise or lateral direction either caused unwanted release of the towel or ultimately damaged parts of the holding device. In this respect it should be noted that when a towel is depending from a holder device of this type the towel may often be used without releasing the towel from the device as by wiping one's hands on the towel from either a position in front of the towel holder or from the side of the towel holder. Such use of a towel for wiping one's hands is frequently done in bowling alleys, in kitchens and by bartenders in bars.

The present invention contemplates a holder means for towels or the like which is so constructed and arranged that the disadvantages of prior devices are obviated and new advantages are achieved. The towel holder means of this invention includes a rugged construction adapted to be mounted on a wall surface without protruding therefrom in a manner which might constitute an obstruction or present a hazardous condition. The present towel holder mounts on a wall with a minimum of protrusion and that part which does protrude has an external configuration which minimizes injury or damage to a person working adjacent thereto as a bartender at a bar. The present towel holder includes a towel receiving and release opening which extends through approximately 360° to facilitate the introduction or acceptance of a towel portion into the holder from substantially any direction in front of the towel holder. The present holder is so designed that guiding the towel portion into the holder opening is facilitated. The present invention includes a towel holding zone of relatively wide area formed by internal converging sector-like surface portions which cooperate with the ball for trapping and gripping the towel portion. The holding means also includes a towel release zone formed by enlarged recess means which so facilitate the release of the towel that a towel may be quickly released from the holder by substantially a single uniform movement of the towel.

The primary object of the present invention is to design and provide a novel holder means for towels and the like.

An object of the invention is to disclose and provide a holder means which embodies a rugged construction, is inexpensively and easily manufactured, and may be readily assembled and attached to a supporting wall surface.

Another object of the invention is to disclose and provide a towel holder means comprising essentially three parts which are readily assembled and which do not re-

2

quire special tooling or close tolerances for fabrication thereof.

Another object of the invention is to disclose and provide a holder means adapted to positively hold the towel while it is being pulled during wiping of the hands from any varying directions.

A specific object of the invention is to design and provide a rugged towel holder construction adapted to readily accept a towel for holding and to quickly release the towel when desired.

Many other objects and advantages of the present invention will be readily apparent from the following description of the drawings in which an exemplary embodiment of the invention is shown.

15 In the drawings:

FIG. 1 is a perspective view of a holder means embodying this invention.

FIG. 2 is a sectional view taken in a vertical plane including and passing through the axis of the holder means 20 in FIG. 1.

FIG. 3 is a sectional view taken in the vertical plane indicated by lines III—III of FIG. 2.

The description of the invention is made with reference to a towel; it will be understood however that the holder means of this invention may be used to hold any relatively thin sheet-like material such as fabrics, paper, cardboards, metal sheet, and such material may include notes, hats, signs, towels, tools, etc. It is intended that the holder means have substantial universal use as a holder for sheet-like objects and that its exterior appearance and shape may be subject to change and modification for providing desired ornamentation. The following description is exemplary and not limiting.

In the drawings a holder means embodying this invention 35 is generally indicated at 10. Holder means 10 comprises front and back circular disc-like members 11 and 12 respectively held in axial spaced relation by hub means 14. Members 11 and 12 may be made of any suitable material such as a rigid plastic or metal. Rigid plastic materials may include styrene, ethyl propylene and other plastic materials capable of being molded and providing a strong rigid non-deformable disc-like member. Metal materials may include aluminum. In some instances it may even be desirable to employ a hard wood.

40 Front and back members 11 and 12 in axial spaced relation define an internal chamber generally indicated at 15 having a peripheral opening 16 extending for approximately 360°. In this example a strut 17 connects the tops of members 11 and 12 and interrupts the continuity of 45 peripheral opening 16. Strut 17 serves to reinforce and hold front member 11 in selected spaced parallel relation with respect to back member 12. Thus peripheral opening 16 is adapted to accept or receive a towel portion through approximately 360°.

50 55 A ball 18 is freely movable and confined in chamber 15 for serving as a releasable locking element for a towel 19 to be held by the holding means. Ball 18 may be made of suitable material such as metal or ceramic. In this example ball 18 is of steel, plated or coated with cadmium or chromium to provide a smooth surface and to resist rusting, corrosion, or any deterioration of the ball surface which might soil or stain a towel. A smooth ball surface also enhances the interengagement of the ball and towel fabric for capture of the ball in a fold of the towel.

60 65 Ball 18 has a diameter greater than the width of the peripheral opening 16 to prevent escape of ball 18 from chamber 15. Ball 18 is normally positioned by gravity at the bottom of chamber 15.

70 75 The internal chamber 15 of the holding means includes a holding zone indicated by H and a release zone indi-

cated by R. The holding zone is defined by internal radially outwardly convergent wedge surfaces 20 and 21 on members 11 and 12 respectively. These convergent surfaces 20 and 21 are in effect sector-like surfaces of a cone when the axis of hub means 14 and the members is considered as coinciding with the axis of the cone. In this example the included angle of the sector-like surfaces is slightly less than 180° and greater than 90°. Thus an extended holding zone is provided which is effective against sidewise or lateral pulls as well as downward pulls on a towel. The internal convergent surfaces 20 and 21 have corresponding base cone angles of not less than 10° and not greater than 25°. In this example the base cone angle is approximately 15°. It has been found that convergent angles of about 15° provide the desired wedging action for holding a towel in the holding zone. Greater than 25° permits the towel to be held in such a loose manner that it might become disengaged from the towel holder and when the convergent surfaces are formed at base cone angles of less than 15° the wedging action is so tight and effective that release of the towel is hampered.

The release zone indicated at R includes internal parallel surfaces 24 and 25 formed respectively on members 11 and 12. The space between surfaces 24 and 25 is approximately the space between the largest portion of the surfaces in the holding zone, namely those adjacent to the axis of the hub means 14. The space between surfaces 24 and 25 is about 1.5 times or more the diameter of wall 18 so that the release zone provides an enlarged upper portion of annular chamber 15. The release zone extends about the axis of the hub means for slightly more than 180° and is then continuous with the holding zone H. If desired the internal surface 24 on front member 11 may be provided with an internal peripheral inclined surface portion 24'.

It should be noted that the diameter of front member 11 is slightly less than the diameter of back member 12 so that forwardly facing edge face 26 on member 12 extends radially beyond the circumference of front member 11. Front member 11 may be provided with a beveled edge face 27 which, together with the smaller diameter of front member 11 as compared to back member 12 assists in guiding a towel portion toward the peripheral opening 16 and the reception of the towel portion in opening 16.

Hub means 14 providing an axial connection between front and back members 11 and 12 may comprise a cylindrical body 30 extending from the internal face of front member 11 and terminating in a reduced end portion 31 provided with a flattened surface 32 thereon. Back member 12 includes a cylindrical boss 33 having a bore 34 adapted to receive the reduced end 31 of cylindrical body 30. Boss 33 is provided with a corresponding mating flattened surface 35 cooperating with surface 32 so that the front and back members are held against rotation. In this example the front and back members may be secured together as by a suitable bonding adhesive applied to the mating surfaces on cylindrical body 30 and cylindrical boss 33.

In another example of this invention the members 11 and 12 may be connected together by a similarly constructed hub means 14 provided with a through bore coaxial with the hub and adapted to receive a screw bolt which may project from the back face of the back member 12 for attachment to the wall surface.

The back member 12 may be coated with an adhesive bonding composition material at the time it is desired to attach the same to a wall for tightly holding the holder means to the wall. For this purpose the holder member may be provided with a small capsule of liquid adhesive, the capsule being suitably secured to the holder device for convenient ready application when desired.

The front face of the front member 11 which is generally circular provides a suitable face for the location

of any selected desirable advertising material. For this purpose the front face of the front member may either carry decals for ornamentation thereof or may bear other suitable artistic and ornamental works.

It should be noted that the depth of the holder means 10 is not great and that its circular configuration with the beveled front edge 27 reduces the likelihood of injury to a person when it may be struck by a person's body.

When it is desired to place a towel in holder 10 an edge or other portion of the towel may be introduced into the holder through the peripheral opening 16 at any place along its circumference. When it is introduced to the chamber 15 the towel is drawn against the ball 18 so as to displace the ball upwardly and permit the ball to fall between a towel portion and the converging surfaces 20 and 21. When the towel is then drawn downwardly the ball is urged into wedging relation with respect to the holding surfaces 20 and 21 and the towel will be tightly held by the cooperation of the ball and the wedge surfaces. Any down pull or side pull on the towel after it is thus connected to the holder means 10 will not release the towel because of the wide holding zone provided by the convergent sector-like surfaces. FIG. 3 shows towel 19 being held by means 10 in positions to show normal holding action and side holding action.

When it is desired to release the towel from the holder means 10 the towel may be pulled upwardly so that the ball 18 is urged into the wider portion of the holding zone and then into the release zone at the upper portion of the holder means 10. Once the ball has been displaced into the release zone it will no longer tightly hold the folds of the towel and the towel may be readily pulled away from the holder means. Release position of the towel and ball is also shown in FIG. 3.

The numbers 11 and 12 may be made in square or other polygonal shape, and may be made to resemble other objects or things for aesthetically conforming to the decoration of the room in which it is used. Any such change in shape may be made while retaining the essential internal configuration of the holding and release zones.

All changes and modifications coming within the scope of the appended claims are embraced thereby.

We claim:

1. A holding means for a towel or the like comprising: front and back disc-like members; means connecting said members in selected spaced axial relation; said disc-like members in said spaced relation defining an internal chamber having a peripheral opening adapted to accept a towel portion through approximately 360°; said internal chamber including a holding zone and a release zone for a towel portion; a ball normally disposed in said holding zone and having a diameter greater than the width of the peripheral opening to retain the ball in said chamber; said holding zone including convergent sector-like internal surfaces on said front and back members, said surfaces extending through an included angle of less than 180° and greater than 90°; said release zone including internal parallel surface portions on said members spaced apart not less than 1.5 times the diameter of the ball and extending through an included angle of greater than 180°.

2. A holding means as stated in claim 1 wherein the diameter of the front member is less than the diameter of the back member to facilitate guiding a towel portion into said peripheral opening.

3. A holding means as stated in claim 1 wherein said convergent surfaces on each of said front and back members have a base cone angle of not less than 10° and not greater than 25°.

4. A holding means as stated in claim 1 wherein said convergent surfaces on said front and back members respectively each include a base cone angle of approximately 15°.

5. A holding means for a towel or the like comprising: front and back circular members; means connecting said members in selected spaced axial relation; said mem-

bers defining an internal chamber having a peripheral opening adapted to accept a towel portion; said chamber including a holding zone and a release zone for the towel portion; a ball normally disposed in said holding zone and having a diameter greater than the width of the peripheral opening to retain the ball in said chamber; said holding zone including internal convergent surfaces on said front and back members; said release zone including internal parallel surface portions on said members spaced apart a distance substantially greater than the diameter of the ball; said peripheral opening leading to said holding zone and to said release zone.

6. A holding means as stated in claim 5 including a ball having a smooth slippery surface.

7. A holding means as stated in claim 6 wherein said ball comprises a steel ball plated with chromium.

8. A device for holding sheet-like material such as a towel or the like comprising: axially spaced front and back members defining therebetween a chamber having a peripheral opening; means connecting said members; a ball element within said chamber; means on said members below said connecting means cooperable with said ball for holding such material; means on said members above said connecting means cooperable with said material for releasing said ball; said peripheral opening pro-

viding means for receiving a portion of the material through approximately 360° and providing means for withdrawing said material through approximately 180°.

9. A device as stated in claim 8 including adhesive means on the back surface of said back member for attachment of the device to a wall.

10. A device as stated in claim 8 wherein said means connecting said members is provided with a through bore, and a screw bolt extending through said bore for engagement with a wall for attachment of the device thereto.

11. A device as stated in claim 8 wherein said front member has a diameter less than said back member, said front member having a front beveled edge whereby guiding of a towel portion to said peripheral opening is facilitated.

12. A device as stated in claim 8 wherein said front member has a front surface adapted to carry advertising media.
